FLUID FLOW RESTRICTOR

Charles A. E. Hensley, Winnipeg, Manitoba,
Canada

Application June 19, 1952, Serial No. 294,325

3 Claims. (Cl. 138—46)

1

The present invention relates to valves for the control of fluids. It is a well known fact that when a closed valve is holding back considerable pressure and is suddenly released, the rush and turbulence of the released fluid passing through the valve results in objectionable noises. The sudden pressure, quickly building up in the previous neutral part of the valve creates strains on the various parts and also on the line being supplied. For various other reasons besides noise, such parts may require the pressure built up in a slower manner.

The principal object of the present invention is to design a fluid flow restrictor of the valve type which, when being opened, will gradually permit increase in the velocity of the escaping fluid and so reduce the above mentioned turbulent rush and accompanying noise, including the sudden strains.

A further object of the invention is to provide a flow restrictor which may or may not be a shut-off valve but will vary the velocity flow of the fluid between pre-determined limits depending on the pressure therebehind.

A further object of the invention is to obtain the above mentioned objects by a novel arrangement of flow retarding baffles which can be progressively reduced as the valve opens.

With the above important objects in view which will become more apparent as the description proceeds, the invention consists essentially in the construction and arrangement of parts hereinafter more particularly described, reference being had to the accompanying drawings in which:

Figure 1 is a sectional view through the flow restrictor and showing half the plunger and the control shaft in side elevation.

Figure 2 is a horizontal sectional view taken on the dot and dash line 2—2, Figure 1.

Figure 3 is a perspective view of the control shaft.

Figure 4 is a perspective view of one of the liners.

In the drawings like characters of reference indicate corresponding parts in the several figures.

The casing of the flow restrictor is formed from three castings namely; a base casting 1, a main casting 2, and a cover casting 3, each of which will be separately described in detail.

The base casting is of an inverted cone-shape having an inlet passage 4 centrally therethrough. The bottom presents an annular flange 5 having holes 6 therein for fastening to a supply pipe (not shown). The upper part of the base casting car-

2

ries an enlarged flange 7 which is secured by bolts 8 to the bottom face of the main casting 2, a suitable gasket 9 being provided therebetween. The dished upper face 10 of the base casting has an annular groove which receives a leather seat 11 for a purpose later described.

The main casting 2 is of cylindrical-form which carries interior, right hand, square, screw threads 12. The lower part has an annular flange 13 which receives the base casting while the upper part carries an annular flange 14 which is secured by bolts 15 to the cover casting, a gasket 16 being inbetween. The upper interior of the casting 2 is cut at a 45° angle to form an annular seat 17, the bottom part of which curves downwardly at 18 to cut back and form an annular baffle groove 19, just above the threads 12. At three equi-distant positions around the threads 12, vertical grooves 20 are cut therein and the lower part of these latter grooves are outwardly stepped, as at 21. Liners 22, shown in Figure 4, are received in the stepped grooves in a press fit. The liners are of rectangular-shape, one side of each being outer stepped, as at 23, to mate with the stepped part 21 of the grooves while the inner side of each is provided with square cross threads 24 which are the same as the threads 12 of the main casting 2.

The cover casting 3 is of an inverted cup-shape, 30 having a lower annular flange 25 which receives the main casting and a side offset 26 having a passageway 27 therein which is encircled by an outer annular flange 28. This latter flange is provided with holes 29 for fastening to an outlet pipe (not shown). The upper interior of the cover casting has a 45° sloping annular face 30 to provide a seat for a purpose later explained. The extreme upper end of the cover casting carries a boss 31 formed with an annular flange 32 on the outside while the centre is bored at 33 with an angular step 34.

A plunger 35 is received within the casting 2. The bottom of this plunger is cone-shaped and adapted to seat on the leather 11 and hold fluid 45 pressure back from the inlet passage 4 when the flow restrictor is shut. The centre of the plunger has a vertical hexagonal-shaped hole 36 therein which stops slightly from the bottom. The outer sides carry right handed square threads 37 which 50 ride in the threads 24 of the liners 22, the thread teeth thereof face the teeth of the threads 12 of the main casting in spaced relation therefrom so that a very thin passage 38 is provided there between and for the lengths of the distances between the liners. The upper end of the plunger

carries a horizontal overlying disc 39 which is secured thereto by bolts 40, a gasket 41 being interposed. The periphery of this latter disc is tapered at a 45° angle on each side, as shown at 42 and 43, so that the lower taper will contact the annular seat 17 when the valve is shut. When the plunger is fully screwed up on the liners the upper taper 43 will contact with the face 30 and the flow restrictor will be fully open. The disc 39 is also centrally provided with a central hexagonal hole 44 which is aligned with the hole 36.

A control shaft 45, best shown in Figure 3, has the lower part 46 thereof hexagonal in shape while the upper end carries a wheel 47 having a control handle 48. The lower end passes through the bore 33 and telescopes into the hexagonal holes 36 and 44 of the plunger. Suitable packing 49 is received in the bored hole 33 and around the shaft 45. A gland 50 also encircles the shaft and sits on the packing while an annular disc 51 sits on the ferrule and can be pulled down thereagainst by tightening the nuts of bolts 52, which are anchored in the flanges 32, and so compress the packing. A cover plate 53 is carried by the disc 51 and holds a split washer 54 which rides in a groove 55 on the control shaft 45.

From the above description and by observing Figure 1, it will be seen that the plunger is held seated on the leather 11 while the disc 39 is held to the seat 17, thus positively closing off any fluid from the inlet passage 4. The seating pressure is obtained through the liners and as the liners are caught in the steps 21 they cannot move upwardly. The control shaft 45 is held fluid tight by the packing 49 and as it is telescoped into the plunger with an hexagonal-shaped connection, the plunger can be screw released from the leather 11 by manual rotation of the wheel 47 in an anti-clockwise direction. When this occurs, the fluid escapes from the inlet passage but must pass up through all the labyrinth of passages between the threads 12 and 37 to reach the outlet passage 27 and it cannot spiral up the threads due to the three blocking liners 22. While the passages 38 between the opposing thread teeth are fairly wide in the drawings, in actual practice they will be calibrated in thousands of an inch so that the fluid, in its passage upward, will have to work past each of the baffles while passing across the relatively large spaces inbetween created by the grooves between the teeth. The total resistance of all the thread baffles will knock the head out of the fluid pressure, so to speak, and therefor a minimum quantity will move therethrough from the inlet passage to the outlet. As the control shaft is unscrewed, each turn will lessen the baffle resistance by one thread and this in turn will increase the fluid flow until all threads are removed and the disc 39 contacts the face 30, at which time the flow restrictor will be completely open and full quantity is passing through. In this manner, the control shaft has, what might be called, a "vernier regulation" over the fluid passage to regulate the velocity and as the pressure in the casing builds up slowly as the valve is opened, noise is practically eliminated. It might be mentioned at this time that, as the fluid leaves the thread baffles, it expands into the enlarged baffle groove 19 and is then restricted again as it passes through the annular space thereabove. This rather coarse baffle permits a large volume of flow but has a further quieting effect, especially when the valve is fully open. Two or more such coarse baffles may be provided if desired.

When the flow restrictor is fully open and the taper 43 of the disc 39 is in contact with the upper annular face 30, the control shaft and packing 49 is shut off from the fluid pressure in the valve casing. Accordingly, the control shaft can be drawn up by releasing the disc 51 and gland 50 and the packing 49 repaired or renewed while the flow restrictor is in service.

From the drawing in Figure 1 it will be seen that all parts of the flow restrictor are readily accessible by releasing the various bolts and nuts. Packing and leathers may be renewed quite easily or seating faces readily ground. The parts are easily made without requiring exacting work and all parts can be assembled without skilled help. The liners are inserted from the bottom of the main casting and the steps 21 prevent upward sliding movement of same under pressure. The split washer 54 insures that the control shaft will not end shift. The plunger threads are firmly held in alignment with the threads of the main casting by the liners and ample thread bearing is provided for a firm pressure of the plunger on the leather seat 11 and against the seat 17. While single threads have been shown, it will be understood that any plurality of threads can be used as required by conditions under which the flow restrictor works. While a leather seat has been shown at the bottom and a metallic seat at the top and both are used, either one may be used separately to shut off the flow at any one side of the thread baffles while the other can be free, and metal or resilient material used on either. In the same way, if the construction is to be used just for variation of flow, the seats could be dispensed with and the fluid just controlled by the adjustable thread baffles in the manner explained. The device is simple in design and operation, sturdy in construction, positive in action, and wear is reduced to a minimum. It will stand up to exacting conditions for many years of useful service.

What I claim as my invention is:

1. A flow restrictor for controlling fluids, comprising: a casing; spiral threads on the interior walls of said casing; a plunger positioned within the threaded part of said casing; exterior spiral threads on said plunger, of the same pitch as said casing threads; inwardly projecting means, carried by the interior walls of said casing, for screwably receiving the threads of, and supporting, said plunger; the thread teeth of said plunger directly opposite and spaced from the teeth of said casing threads; fluid inlet and outlet passages in the walls of said casing, interconnected by the spacing between said plunger and casing threads; and means for rotating said plunger.

2. A flow restrictor for controlling fluids, comprising: a casing; spiral threads interiorly of said casing; liners, mounted on the inner walls of said casing, at said thread area, and in spaced relation theraround; a plunger positioned within said casing; said plunger threadedly mounted within and on said liners with spiral threads of the same pitch as said casing threads, and with the thread teeth thereof directly opposite and spaced from the teeth of said casing threads; fluid inlet means to said casing, adjacent one end of said plunger; fluid outlet means from said casing, adjacent the opposite end of said plunger; and exterior means for rotating said plunger on said liners.

3. A flow restrictor for controlling fluids, comprising: a hollow casing having an intake passage thereto and an outlet passage therefrom; spiral threads formed on the interior walls of said cas-

ing, between said passages; grooves across said threads at spaced intervals therearound; toothed liners received in said grooves, with said teeth facing inwardly of said casing; a plunger; spiral threads formed on the exterior of said plunger, of the same pitch as said casing threads, and screwable with the teeth of said liners; said plunger supported on said liners with the thread teeth thereof directly opposite and spaced from the teeth of said casing threads; a control shaft 10 bearinged through said casing and telescopically received by said plunger for operable rotation thereof; and means for rotating the exterior end of said control shaft.
